(57) **CLAIM**

The ornamental design for a lock, as shown and described.

DESCRIPTION

FIG. 1 is a perspective view of another embodiment of the lock in the case;

FIG. 2 is a perspective view from another angle of FIG. 1;

FIG. 3 is a front elevational view of FIG. 1;

FIG. 4 is a rear elevational view of FIG. 1;

FIG. 5 is a left side elevational view of FIG. 1;

FIG. 6 is a right side elevational view of FIG. 1;

FIG. 7 is a top plan view of FIG. 1;

FIG. 8 is a bottom plan view of FIG. 1; and,

FIG. 9 is an exploded perspective view of the lock.

The broken lines shown in the drawings represent portions
of the lock that form no part of the claimed design.
